SYNCHRONIZING SYSTEM

James N. Whitaker, Tuckahoe, N. Y., assignor to
 Radio Corporation of America, a corporation of
 Delaware

Application October 8, 1938, Serial No. 233,927

16 Claims. (Cl. 178—69.5)

This invention relates to synchronizing and automatic framing methods and apparatus, and more particularly, to synchronizing and automatic framing methods and apparatus applicable to facsimile and television systems in which the speed of the recording mechanism is controlled by received signals supplied to a local oscillator during time intervals determined by the speed of the recording mechanism.

10 My new method and apparatus for accomplishing synchronization has the beneficial effect of not only providing accurate synchronizing with a minimum of apparatus, but also provides at the same time automatic framing of the received image so that the entire installation is further simplified by eliminating the necessity for providing framing apparatus.

15 A further feature of my invention is the fact that the received signals for synchronizing are derived directly from the signals representative of the image or message transmitted.

20 In accordance with my invention, a portion of the received signals is fed through a commutator to a local oscillator. The local oscillator supplies the synchronizing power either in part or in whole to the recording mechanism. The commutator through which the received signals are fed to the local oscillator, is controlled by the recording mechanism, and the commutator is so arranged that the received signals are fed to the oscillator during time intervals when the frequency deviates from that frequency necessary to maintain the apparatus in synchronism. It will 25 thus be appreciated that my invention differs from known synchronizing methods in the use of a commutator whose speed is determined by the speed of the recording mechanism and in which a local oscillator supplying the synchronizing energy has its frequency controlled by the commutator acting in conjunction with received signals. By suitably selecting the number of segments on the commutator with regard to the speed of the recording mechanism, it is possible to provide at 30 the same time automatic framing or phasing of the received record.

35 Accordingly, it is one of the objects of my invention to provide an improved synchronizing method and apparatus for facsimile and television systems.

40 Another object of my invention is to provide an improved synchronizing method and apparatus together with automatic framing for facsimile and television systems.

45 A further object of my invention is to provide a

50 synchronizing system for facsimile and television apparatus in which the synchronizing signals are derived from the signals representative of the image to control a local oscillator for regulating the speed of the receiving equipment by using a commutator whose speed is controlled by the local source of oscillations and at the same time to restrict the effectiveness of the incoming signals to control the frequency of the oscillator so as to provide correct phasing or framing of the received image.

55 Other objects of my invention will become clear to those skilled in the art upon a reading of the following detailed description taken together with the drawings.

60 In the drawings, Fig. 1 shows in block diagram one embodiment of my invention showing schematically the use of energy derived from received signals to control the local oscillator through a commutator;

65 Fig. 2 shows in block diagram form a modification of the form of the invention shown in Fig. 1, in which a shorting bar commutator replaces the magnetic commutator shown in Fig. 1;

70 Fig. 3 shows a further embodiment of my invention in a modified form of both Figs. 1 and 2, in which a synchronous motor replaces the phonic wheel shown in Figs. 1 and 2; while

75 Fig. 4 shows in schematic diagram in more detail, the electrical circuits associated with the synchronous motor and commutator shown in Fig. 3.

80 In describing my invention, for convenience it will be assumed that the invention is to be used in connection with tape facsimile systems. In such a system, the transmitter may be of the type shown and disclosed in the application of G. L. Dimmick, entitled "Scanning device," which was filed September 21, 1937, and bears application Serial Number 164,847. In such a scanner the essential components comprise a motor, a tape feed mechanism upon which the message to be transmitted is transcribed, a source of light, an optical system, means for moving the light beam across the tape, and a photoelectric cell with its associated amplifier system. The drive motor may be of the synchronous 60 cycle per second type. The tape feed system comprises a sufficient number of rollers and guides to draw the tape past the scanning point at a constant speed.

85 The light source, which may conveniently be a pre-focused projection electric lamp, has interposed between it and the tape an optical system for producing a sharply focused beam of light of small 90 95

area upon the tape. Interposed between the optical system and the tape there is provided, for example, a rotating polygonal prism to cause the beam of light to sweep across the tape in a direction perpendicular to the motion of the tape. Alternatively, there may be provided a scanning disk having a number of small apertures spaced equi-distant around the periphery of the disk and at equal radial distances from the center of the disk. The reflected light from the tape is projected upon the photoelectric cell so as to convert the varying quantity of reflected light into electrical signals of varying amplitude. A suitable amplifier amplifies the produced electrical signals and the output of the amplifier may then be used to suitably modulate a transmitter or the output may be impressed upon a transmission line.

It will be appreciated that during the scanning process, since the scanning takes place at a predetermined rate, the generated electrical signals produced by the conversion of light will produce signal components of a frequency which bear a fixed relation to the scanning frequency or rate, in addition to those signals having frequency components related to the varying density of the scanned record. This fact is well known in the art and is treated in considerable detail in the paper by Mertz and Gray, entitled "A theory of scanning and its relation to the characteristics of transmission signals in telephotography and television," which appeared in the Bell System Technical Journal, volume 13, No. 3, July 1934, page 464 et seq. Thus, for example, if the scanning rate is 60 cycles per second, there will be produced during the scanning process frequency components bearing harmonic relation to 60 cycles, namely, 60 cycles, 120 cycles, 180 cycles, 240 cycles, etc. Use is made of these generated signals transmitted to the receiving point at the receiving point for controlling the speed of the recording mechanism as will be described in more detail below.

Turning now to Fig. 1, the transmitted signals are impressed after suitable detection and amplification, if necessary, upon the recording amplifier 13. The output of the recording amplifier 13 may be conveniently in the form of push-pull signals and fed to the recorder from the terminals 31. The recorder may conveniently take the form of that shown in United States Patent No. 2,104,109 to C. J. Young for "Apparatus for facsimile recording," issued January 4, 1938. The output of the recording amplifier 13 is also fed to an oscillator 15 through a magnetic commutator comprising the core 25 having an air gap, and windings 27 and 29. The recording spiral 23 of the recorder is of such dimensions and so positioned as to lie within a portion of the air gap of the core 25. It will be appreciated, of course, that the recording spiral 23 is mounted on the shaft 22 of the drive motor 21 so that the recording spiral during rotation varies the reluctance of the magnetic path by interposing more or less magnetic material during its rotation. It will be appreciated that the recording spiral made of magnetic material, such as hardened steel for example, during the interval when the spiral ridges lie parallel to the plane of the core, shortens the air gap and provides a maximum magnetic material path, while during the intervals where the spirals are substantially perpendicular to the plane of the core, the air gap has been lengthened while the magnetic material path has been decreased under which con-

ditions maximum reluctance of the path is provided.

It will thus be appreciated that during the rotation of the spiral, the voltage transferred from the winding 27 to the winding 29 will vary in accordance with the reluctance of the path of the core 25, so that the intensity of the signals fed to the oscillator 15 will likewise vary in accordance with the rotation of the spiral. The oscillator 15 has its output fed to an amplifier 17 whose output in turn is fed to a phonic wheel 19 mounted on a shaft 20 of the drive motor 21. It will thus be seen that the alternating current fed to the phonic wheel 19, which in effect acts as a synchronous motor, will control the speed of the drive motor 21 at a rate determined by the frequency of the oscillator 15. The use of a phonic wheel for this purpose, is, of course, well known in the art, as typified for example by the United States Patent No. 1,738,673 to Schröter, for "Synchronizing arrangement for picture transmission," issued December 10, 1929. Inasmuch as the oscillator 15 is to have its frequency controlled by the received signals impressed on the signal input 11, it is necessary to provide an oscillator having fair frequency stability whose frequency, however, is capable of being controlled by injecting during periodic intervals a small amount of controlled energy. An oscillator suitable for this purpose may conveniently take the form of a dynatron oscillator of the type disclosed in United States Patent No. 2,067,366, issued to James N. Whitaker, January 12, 1937, for "Dynatron oscillator circuit."

In operation, the received signals impressed on the signal input and passed through the magnetic commutator to the dynatron oscillator will have their intensity controlled, of course, by the position of the recording spiral 23 at the moment during which signals are actually being received. Since the position of the recording spiral is determined by the speed of the drive motor, which in turn is controlled through the phonic wheel by the oscillator, it will be readily appreciated that if the drive motor is running at a speed different from that of the motor of the transmitting equipment, the spiral has such a position as to give minimum reluctance of the path, so that a relatively strong signal is passed through the magnetic commutator to the oscillator to shift its frequency in such a direction as to put the speed of the phonic wheel and drive motor in synchronism with the transmitting motor. If the drive motor is running at synchronous speed, then the recording spiral is in such a position as to provide maximum reluctance so that the received signals, being greatly attenuated due to the increased reluctance, are ineffective to change the oscillator frequency.

During the scanning of the tape at the transmitter at the moment when the scanning of one line is completed and the scanning of the following line is about to commence, there is produced a marginal impulse. If the marginal impulse is received at the time when the spiral tooth is in a position to provide minimum reluctance, and hence maximum transfer of energy, the dynatron oscillator's frequency will be synchronized with the impulse. Inasmuch as the marginal impulse occurs at the end of each line, it will be appreciated that framing likewise takes place of the receiving equipment.

While this method and apparatus affords excellent synchronizing and framing, it will be appreciated that the design of the magnetic com-

mutator together with the necessity for positioning the commutator in close proximity to the recording spiral makes it desirable to simplify the commutation apparatus. Accordingly, an improved form of my invention is shown in Fig. 2, in which the magnetic commutator is replaced by a more conventional type of shorting bar commutator mounted on the shaft of the drive motor.

Turning to Fig. 2, it will be noted that mounted on the shaft 22 of the drive motor is the shorting bar commutator 43 comprising a hub of insulating material such as Bakelite, for example, imbedded in which there is a plurality of metallic conducting segments 45-45 which may take the form of copper bars, mounted on the periphery equi-distant from each other and parallel to the axis of the commutator. A pair of brushes 47 and 49 bear across each segment or shorting bar in succession as the commutator is rotated. Signals from a recording amplifier 13 are capacitatively coupled through the condenser 51 to the oscillator 15 through the brushes 47 and 49 and the commutator 43. Thus, for example, when one of the segments 45 is in contact with the brushes 47 and 49, any signals present in the output of the amplifier 13 will be passed to the oscillator 15. When the copper segment bars 45 are not in contact with the brushes 47 and 49, the circuit between the recording amplifier 13 and the oscillator 15 is open, so that no signals can be passed to the oscillator. In other respects the synchronizing equipment and method of operation is identical with that described above in connection with Fig. 1. Under these conditions, it will be appreciated that the synchronizing and framing is improved over that of the system shown in Fig. 1 in view of the fact that a much better differentiation in amplitude between the periods during which signals are fed to the oscillator and those periods during which no signals are fed to the oscillator is provided by the shorting bar commutator than by the magnetic type commutator.

As an alternative form of synchronizing, the modification of my invention shown in Fig. 2 may substitute a synchronous motor for the drive motor and phonic wheel combination, as shown in Fig. 3. In this modification, instead of merely supplying synchronizing power to the phonic wheel while the bulk of the drive power is supplied by a drive motor having inherently poor speed regulation, the output of the oscillator 15 is amplified to a greater extent by the amplifier 63 and the output fed directly to the synchronous motor 65. Under these conditions the synchronous motor will, of course, maintain a speed which is determined uniquely by the dynatron oscillator 15 and as is well known in the art, its speed is determined at all times by the frequency of the dynatron oscillator. This arrangement has the beneficial effect of overcoming "hunting" which may be present in the phonic-wheel-drive motor type of synchronizing system. It is in this case, of course, that the amplifier 63 is called upon to supply all of the power. But this does not lead to any particular complexity or difficulties in view of the fact that the total load on the synchronous motor is generally small, so that 15 watts output of amplifier 63 is sufficient to drive the motor under all load conditions. While the amplifier 63 in general must have greater output than the amplifier 17 feeding the phonic wheel 19, nevertheless the lack of "hunting" of the system shown in Fig. 3 is such a desirable feature that it is gen-

erally preferred to the form of synchronizing shown in Figs. 1 and 2 for example. In all other respects, however, the modification shown in Fig. 3 is substantially identical with that shown in Fig. 2.

In Fig. 4 I have shown in detail schematically the apparatus shown in block diagram form in Fig. 3. Turning to Fig. 4 it will be noted that there is provided the recorder comprising the tubes VT₁, VT₂, VT₃, VT₄ and VT₅ together with their associated components and the synchronizing equipment comprising the tubes VT₆, VT₇, VT₈, VT₉ and VT₁₀ and their associated components. In the drawing VT₁ together with its associated components comprises the first stage of an amplifier for amplifying the received signals impressed on the signal input. It will be recognized that this is a conventional type of transformer coupled input with potentiometer control for regulating the intensity of the incoming signals at P₁. The tube is self-biased by the resistor-capacitor combination R₁C₁. The output, after being amplified, is fed through the transformer T₂ to the diode-triode VT₂ which performs four functions. In the first place, the two diodes act as a full wave rectifier for the amplified signal. Secondly, the triode portion of this type acts as a limiter by providing suitable values of R₂ and C₂ across which the rectified signal voltage is impressed. The output of VT₂ is used to operate the marking tube VT₅ and a portion of the output is also used to operate the reversing tube VT₃. The reversing tube VT₃ operates the spacing tube VT₄ of the push-pull drive amplifier and the outputs of the tube VT₄ and VT₅ operate the facsimile recording head by driving the printer bar 71 against the recording spiral 23. It will be noted that a portion of the output of the tube VT₅ is fed through the capacitor C₃ and commutator 43 to the grid input circuit of the tube VT₆. The tube VT₆ is a dynatron oscillator and there is provided a potentiometer P₂ in its control circuit so as to regulate the amplitude of the energy fed through the condenser C₃ and the commutator 43 to control the frequency of the dynatron oscillator. It will be appreciated, of course, that the frequency of the dynatron oscillator in this arrangement is determined by the magnitude of the biasing voltage provided by the resistor R₁₃ and condenser C₄, as well as the superimposed voltage derived from the output of the tube VT₅. The marginal impulses which serve to control the frequency of the dynatron oscillator also, as pointed out above, serve as framing signals. In this connection, it is, of course, important to note that the number of segments or shorting bars 45 on the commutator 43 must bear a predetermined relation to the number of entries of the recording spiral. Thus if a single entry spiral is used, the commutator would only have one short circuiting bar. If a six entry spiral is used, six short-circuiting bars are recorded, assuming that both the spiral and commutator are operated at the same shaft speed. If it should be desirable from the standpoint of mechanical design to operate the spiral and commutator at different shaft speeds, the number of shorting bars on the commutator must be such as to maintain the relationship noted above, namely, that the number of traversals of the spiral per second must be equal to the number of traversals of the shorting bar per second.

The output of the dynatron oscillator VT₆ is capacitively coupled to a conventional two-stage amplifier comprising the tubes VT₇ and VT₈. The output of the second stage of the amplifier

VT₈ is then utilized to drive a push-pull stage VT₉ and VT₁₀ and the size of the tubes are so chosen as to deliver approximately 25 or 30 watts of energy for feeding the synchronous motor 65 which may have a rating of 1/200 horse power, for example.

From a consideration of Fig. 4 and its description, it is to be noted that the synchronizing system provided is one of extreme simplicity, 10 since the only additional mechanical equipment is the commutator 43 which can, of course, conveniently be mounted on the motor shaft and the relatively simple electronic circuit comprising the dynatron oscillator VT₆ and the amplifier comprising the tubes VT₇ through VT₁₀. Yet, 15 it will be appreciated that even though the circuit arrangement and apparatus is of extreme simplicity, this system is capable of maintaining faithful synchronizing and at the same time providing the very desirable feature of automatic framing.

Having described my invention, what I claim is:

1. The method of synchronizing recording apparatus which comprises the steps of providing a local source of wave energy, controlling the speed of the recording apparatus from the source of wave energy, receiving remotely generated image recording signals, amplifying the received 25

signals, deriving wave energy from the amplified received signals, feeding the derived energy to the local source of wave energy to control the frequency of the wave energy from the source, and controlling the time duration during which 30 the derived energy is effective to control the frequency of the local source of wave energy in accordance with the speed of the recording apparatus.

2. The method of synchronizing recording apparatus which comprises the steps of providing a local source of wave energy, driving the recording apparatus from the source of wave energy, receiving remotely generated image recording signals, amplifying the received signals, deriving wave energy from the amplified received signals, feeding the derived energy to the source of wave energy to control the frequency of the wave energy from the source, and controlling the time duration during which the derived energy 40 is effective to control the frequency of the source of wave energy in accordance with the speed of the recording apparatus.

3. The method of synchronizing a rotating motor which comprises the steps of providing a local source of wave energy, controlling the speed of said motor from the source of wave energy, receiving remotely generated image recording signals, amplifying the received signals, deriving wave energy from the amplified received signals, periodically feeding the derived energy to the source of wave energy to control the frequency of the wave energy from the source, and controlling the periodicity at which the derived energy is effective to control the frequency of 50 the source of wave energy in accordance with the speed of said motor.

4. The method of synchronizing recording apparatus which comprises the steps of providing a local source of wave energy, controlling the speed of the recording apparatus from the source of wave energy, receiving remotely generated image recording signals, amplifying the received signals, deriving wave energy from the amplified received signals, and feeding the derived energy 55 to the source of wave energy to control the frequency of the wave energy from the source whenever the speed of the recording apparatus deviates from a predetermined value.

5. The method of synchronizing a rotating motor which comprises the steps of providing a local source of wave energy, controlling the speed of the motor from the source of wave energy, receiving remotely generated image recording signals, amplifying the received signals, deriving wave energy from the amplified received signals, feeding the derived energy to the source of wave energy to control the frequency of the wave energy from the source whenever the speed of the motor deviates from a predetermined value.

6. Synchronizing apparatus comprising a local 15 source of wave energy, means for controlling the speed of recording apparatus from the source of wave energy, means for receiving remotely generated image recording signals, means for amplifying the received signals, means for deriving wave energy from the amplified received signals, means for feeding the derived energy to the source of wave energy to control the frequency of the wave energy from the source, and means for controlling the time duration during 20 which the derived energy is effective to control the frequency of the source of wave energy in accordance with the speed of the recording apparatus.

7. Synchronizing apparatus comprising a local 30 source of wave energy, means for driving recording apparatus from the source of wave energy, means for receiving remotely generated image recording signals, means for amplifying the received signals, means for deriving wave energy 35 from the amplified received signals, means for feeding the derived energy to the source of wave energy to control the frequency of the wave energy from the source, and means for controlling the time duration during which the derived energy is effective to control the frequency of the source of wave energy in accordance with the speed of the recording apparatus.

8. Synchronizing system comprising a rotating motor, a local source of wave energy, means for 40 controlling the speed of said motor from the source of wave energy, means for receiving remotely generated image recording signals, means for amplifying the received signals, means for deriving wave energy from the amplified received signals, means for periodically feeding the derived energy to the source of wave energy to control the frequency of the wave energy from the source, and means for controlling the periodicity at which the derived energy is effective to control the frequency of the source of wave energy in accordance with the speed of the recording apparatus.

9. Synchronizing apparatus comprising image recording apparatus, a local source of wave energy, means for controlling the speed of the recording apparatus from the source of wave energy, means for receiving remotely generated image recording signals, means for amplifying the received signals, means for deriving wave energy from the amplified received signals, and 50 means for feeding the derived energy to the source of wave energy to control the frequency of the wave energy from the source whenever the speed of the recording apparatus deviates from a predetermined value.

10. Synchronizing apparatus comprising a rotating motor, a local source of wave energy, means for controlling the speed of the motor from the source of wave energy, means for receiving remotely generated image recording sig- 75

nals, means for amplifying the received signals, means for deriving wave energy from the amplified received signals, means for feeding the derived energy to the source of wave energy to control the frequency of the wave energy from the source whenever the speed of the motor deviates from a predetermined value.

11. In combination, an alternating current oscillator, means to amplify energy from the oscillator, a motor, means to control the speed of the motor from the amplifying means, a commutator driven by the motor, means to receive picture recording signals, and means to feed a portion of the received recording signals to the oscillator through said commutator, whereby the oscillator is controlled by the received energy in accordance with deviation of the motor speed from a predetermined value of speed.

12. In combination, an alternating current oscillator, an amplifier for amplifying wave energy from the oscillator, a motor, a phonic wheel connected to said motor, means to feed energy from the amplifier to the phonic wheel, a commutator driven by said motor, an image recording amplifier, means to feed remotely generated image signals to said amplifier, and means to feed energy from the recording amplifier to the oscillator through the commutator.

13. In combination, an alternating current oscillator, an amplifier for amplifying wave energy from the oscillator, a motor, a phonic wheel connected to said motor, means to feed energy from the amplifier to the phonic wheel, a magnetic commutator driven by said motor, a recording amplifier, and means to feed energy from the

recording amplifier to the oscillator through the magnetic commutator.

14. In combination, an oscillator supplying wave energy, an amplifier for amplifying wave energy from the oscillator, a synchronous motor, means to drive the synchronous motor by energy from the amplifier, a commutator driven by the synchronous motor, a receiving amplifier, means to supply signals representative of an object to be reproduced to the receiving amplifier, and means to supply a portion of the amplified received signals to the oscillator through the commutator.

15. In combination, an oscillator supplying wave energy, an amplifier for amplifying wave energy from the oscillator, a synchronous motor, means to drive the synchronous motor by energy from the amplifier, a commutator driven by the synchronous motor, a receiving amplifier, means to supply signals representative of an object to be reproduced combined with synchronizing signals to the receiving amplifier, and means to supply a portion of the amplified received signals to the oscillator through the commutator.

16. In combination, an oscillator supplying wave energy, an amplifier for amplifying wave energy from the oscillator, a synchronous motor, means to drive the synchronous motor by energy from the amplifier, a commutator driven by the synchronous motor, a receiving amplifier, means to supply synchronizing signals to the receiving amplifier, and capacitative means to supply a portion of the amplified received signals to the oscillator through the commutator.

JAMES N. WHITAKER. 35
